UNITED STATES PATENT OFFICE.

CHARLES H. MILLER, OF WEST PITTSBURG, PENNSYLVANIA, ASSIGNOR TO SAFETY-
ARMORITE CONDUIT COMPANY, OF PITTSBURG, PENNSYLVANIA, A CORPORATION
OF PENNSYLVANIA.

CONDUIT FOR ELECTRIC WIRES.

942,788.

Specification of Letters Patent.

Patented Dec. 7, 1909.

Application filed July 25, 1907. Serial No. 385,518.

To all whom it may concern:

Be it known that I, CHARLES H. MILLER, a citizen of the United States, of West Pitts-
burgh, in the county of Lawrence, Pennsyl-
vania, have invented a new and useful
5 Conduit for Electric Wires, of which the
following is a full, clear, and exact descrip-
tion, reference being had to the accompany-
ing drawings, forming part of this specifici-
10 cation, in which—

Figure 1 is an elevation partly in section
showing one form of my improved conduit;
Fig. 2 is a cross-section of the same; and Fig.
3 shows a modified form.

15 My invention relates to the class of flexi-
ble conduits, and is designed to provide a
strong, simple and durable structure of this
character which may be cheaply made and
will present a smooth inner surface.

20 In Figs. 1 and 2, I show the conduit as
having an inner lining 2, of woven paper.
This woven paper is formed on a mandrel
and consists of helically wound strips of
25 paper extending in opposite directions and
interwoven or braided so as to form a tubu-
lar structure. Thus one strip runs over the
strip running in the opposite direction, un-
der the next, over the next, and so on.

30 3 is a layer of helical paper or wooden
strip or strips wound over the braided paper
tube; and 4 is a tubular or woven braided
fabric, inclosing the helical paper winding
and saturated with a waterproofing com-
35 pound. The cotton or material for braid-
ing or weaving the tubular fabric may be
treated to fireproof it before it is formed
into the tube; and the winding may be
formed of wooden or other strips instead of
paper strips.

40 In Fig. 3, I show a similar view except
that the woven or braided paper tube is
first covered with a tubular woven or braid-
ed fabric 5, over which is wound the helical
paper strip or strips 3^a, 4^a being the outer
45 woven or braided tubular fabric. In this
case, both tubular fabrics are preferably sat-
urated with waterproofing compound, and
the outer fabric may be coated with mica
flakes, or other non-inflammable material, if

desired, to make the conduit more fireproof. 50
This mica will become embedded in the com-
position.

The advantages of my invention result
from the woven inner layer of paper strips,
in connection with a braided or woven tubu- 55
lar fabric. This gives a smooth inner layer
and also the requisite stiffness and flexing
qualities.

Variations may be made in the form and
arrangement of the parts without departing 60
from my invention.

I claim:

1. A flexible conduit for electric wires,
having an inner lining of woven or braided
strips, the weft and warp strips being spi- 65
rally wound in opposite directions; substan-
tially as described.

2. A flexible conduit for electric wires,
having an inner lining of woven or braided
strips, the weft and warp strips being spi- 70
rally wound in opposite directions, and a
waterproofed tubular braided or woven fab-
ric around said inner layer; substantially as
described.

3. A conduit for electric wires, having an 75
inner lining of woven or braided paper
strips, the weft and warp strips being wound
in opposite directions, a succeeding layer of
spirally wound strip, and an outer braided
or woven tubular fabric saturated with a 80
waterproofing compound; substantially as
described.

4. A conduit for electric wires, having an
inner lining of woven or braided paper
strips, the weft and warp strips being spi- 85
rally wound in opposite directions, a suc-
ceeding layer of spirally wound strips of
paper, and an outer braided or woven tubu-
lar fabric saturated with waterproofing com-
pound; substantially as described.

5. A conduit for electric wires, having an
inner layer of woven or braided paper
strips, the weft and warp strips being wound
spirally in opposite directions, a tubular 95
woven or braided fabric surrounding said
inner layer, a spirally wound paper strip
surrounding the fabric, and an outer woven
or braided tubular fabric, both of said fab-

rics being saturated with a waterproofing compound; substantially as described.

6. A conduit for electric wires having an inner lining of woven or braided strips of paper, the weft and warp strips being wound spirally in opposite directions; substantially as described.

In testimony whereof, I have hereunto set my hand.

CHARLES H. MILLER.

Witnesses:

JOHN MILLER,
H. M. CORWIN.
